UNITED STATES PATENT OFFICE.

CHARLES LEWIS, OF AMSTERDAM, N. Y., ASSIGNOR OF ONE-HALF TO THE
R. TOMLINSON SPRING AND AXLE WORKS, OF BRIDGEPORT, CONN.

MACHINE FOR BENDING AND FORMING SPRINGS.

SPECIFICATION forming part of Letters Patent No. 286,318, dated October 9, 1883.

Application filed June 13, 1883. (No model.)

To all whom it may concern:

Be it known that I, CHARLES LEWIS, a citizen of the United States, residing at Amsterdam, in the county of Montgomery and State 5 of New York, have invented certain new and useful Improvements in Machines for Bending and Forming Springs; and I do hereby declare the following to be a full, clear, and exact description of the invention, such as will enable 10 others skilled in the art to which it appertains to make and use the same.

My invention relates to certain novel and useful improvements in machines for bending and forming springs, and has for its object to 15 provide a device simple and economic in construction, while at the same time the action of the bending-rods shall be constant and ready of adjustment; and with these ends in view my invention consists in arranging the bending 20 bars or slides within a frame, so as to lie side by side in the same horizontal plane, and providing them with ratchet-teeth on their upper surfaces, with which bell-crank levers having 25 adjustable weights at their outer extremities engage to force them forward more or less, in order to conform to the curvature or contour of the former.

My invention also consists in providing a 30 vertically-adjustable fulcrum for the levers, whereby they may be raised out of engagement with the ratchet-teeth, all of which will hereinafter be fully and in detail explained, and then specifically designated by the claims.

In order that those skilled in the art to which 35 my invention relates may more fully understand its construction and operation, I will proceed to describe the same in detail, referring by letter to the accompanying drawings, forming a part of this specification, in which—

Figure 1 is a perspective view, illustrating the position and relation of the several parts with the spring bent by the bending bars or slides to conform to the shape of the former; Fig. 2, a side elevation, showing the means for 40 raising and lowering the fulcrum of the levers, and Fig. 3 a plan view, showing the spring before it is bent, the bending-bars being in the position to form it properly against the former, and also illustrating a grate for the purpose of 45 affording an escape for the water used in this connection.

Similar letters denote like parts in the several figures of the drawings.

A is the frame, within which are placed, side by side, the bending-bars B, in such manner as 55 to slide freely against each other in a horizontal plane.

C are standards which support a rod, D, which acts as a pivot to the bell-crank levers E. The rear ends of these levers pass over a 60 supporting-rod, F, secured within posts G.

H is a bar secured to the posts G and bearing against the sliding bars B, thereby preventing any upward displacement of the same. The forward extremities of the bell-crank levers are adapted to engage with ratchet-teeth 65 I in the upper surfaces of the bending-bars B for the purpose of adjusting said rods forward, as will be presently explained.

J is the former, which is shaped to correspond with the desired shape of the spring. This former is adapted to be plunged in a horizontal plane against the spring, which is placed 70 between the former and the bending-bars.

The operation of my improvement is as follows: The spring is placed in the position, as above set forth, and the former is set up against said spring in any suitable manner. The bending-bars are then adjusted by means of the levers, so as to conform to the contour of the 75 former J. I am enabled to adjust the bars by means of weights K, arranged on the rear ends of the levers. Should it become desirable to throw the levers out of engagement with the ratchet-teeth, so as to withdraw the bending-rods, this may be readily accomplished by simply raising the fulcrum or pivotal point by means of the jack-screw L, which is arranged within the standards C, so as to operate against the bearing M of the rod D. 85

N is a grate, which is placed underneath the field of operation of the plunger, and is a very material advantage in devices of this description, as it affords a ready exit for the water.

It will be observed that the frame within 95 which the bending-bars are held is stationary, and that the former is movable, which arrangement is an important feature, since the constant wearing out of the frame and the bending devices at present used is mainly due to 100 the fact that their movement forward and backward wrenches and racks them. Should it be

come necessary to put in a new bending-bar, this may readily be accomplished, as the length of the rod is not material, and I use no spring movements whatever. I am enabled to produce more or less pressure by the simple adjustment of the weights on the levers, whereas in the devices as at present used the adjustment is brought about by springs and threaded rods in a movable frame.

10 Having thus described my invention, what I claim as new, and desire to secure by Letters Patent, is—

15 1. In a machine for bending springs, the former adapted to be forced against the spring, in combination with the bending-bars having ratchet-teeth, and levers adapted to engage therewith, substantially as set forth.

15 2. The bell-crank levers, pivoted as de-

scribed, and having weights on their rear ends, and adapted at their forward extremities to engage with ratchet-teeth in the upper surfaces of the bending-bars, substantially as and for the purposes set forth.

3. The levers E, pivoted on rod D within the standards C, and supported by the rod F, and having at their rear ends adjustable weights K, in combination with the bars B, provided with ratchet-teeth I, and movable former J, substantially as described.

10 In testimony whereof I affix my signature in presence of two witnesses.

CHARLES LEWIS.
